Attorney

UNITED STATES PATENT OFFICE

EVERETT E. DEHART, OF OMAHA, NEBRASKA

OIL BURNER RETORT

Application filed October 27, 1930. Serial No. 491,481.

The principal object of this invention is to provide a retort for oil burners that will not melt or burn down or crack when in use.

A further object of my invention is to provide a retort for oil burners that is efficient in use and of exceptionally long life.

A still further object of my invention is to provide a retort for oil burners that is not subject to the collection of soot, but if for any reason the same should become fouled, may easily and quickly be taken apart for cleaning purposes.

A still further object of this invention is to provide an oil burner retort that is economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawing, in which:

25 Fig. 1 is a side view of my invention.

Fig. 2 is a cross sectional view of the device taken on line 2—2 of Fig. 1.

Fig. 3 is a top plan view of a portion of one of the upper forward corners of the 30 retort pot.

This retort is designed to be used as an oil burner throwing the flame downwardly as distinguished from oil burners throwing the flame straight into the furnace or throwing the flame upwardly in the fire box of the furnace. Perhaps the best location of my retort relative to the furnace is in the door of the furnace, as in this position the flame will be projected down into the grate or original fuel position of the furnace.

I have used the numeral 10 to generally designate the pot portion of the retort and the numeral 11 to generally designate the lid portion. Extending rearwardly from and completely across the rear end of the pot at its upper portion is the rectangular inlet pipe 12. This rectangular portion is integrally formed on the pot and communicates with the inside of the pot as shown by dotted lines in Fig. 1. This portion 12 is designed

to extend through an opening formed in the furnace, and in communication with a source of air under pressure. As is well known most oil burners use a common centrifugal fan operated by a prime mover for discharging air into the member 12, from which it enters the pot portion. When the member 12 is extending in an opening of the furnace or the door of the furnace, the pot portion will be inside the furnace. In order to securely hold the retort in proper position with the member 12 extending through the furnace I have provided a vertical flange 13 integrally formed on the rear upper portion of the pot as shown in the drawing.

This flange has bolt hole openings 14 through which ordinary bolts pass and also pass through holes drilled in the furnace or door of the furnace. By this arrangement to mount the retort in proper position on the furnace the same is accomplished by only two ordinary bolts. The retort is also additionally supported by having its square rear end engaging the inner surface of the furnace or door of the furnace.

The upper marginal edge of the two side walls of the pot extends forwardly and downwardly as shown in Fig. 1, and upon which the lid 11 rests. This lid 11 has a forwardly and downwardly extending bill portion 15 integrally formed on its forward end. It will here be noted that this bill portion extends a considerable distance beyond the forward end of the pot 10. The numeral 16 designates a lug integrally formed at each side of the lid and in the rear of the bill portion 15. These lugs each engage a depression 17 formed in the pot as shown in Fig. 3 and which are located at the forward upper end of each of the sides of the pot, respectively. These lugs by entering the depressions 17 properly position and hold the lid on the pot 10. However, to remove the lid 11 from the pot 10 it is merely necessary to lift upwardly on the lid 11 until the lugs 16 are clear of the depression 17. The lid is as easily replaced. The numeral 18 designates a downwardly extending baffle member integrally formed on the rear end portion of the lid 11. When the lid 11 is on the pot 10, the lower end of this

baffle member 18 extends below the lowest portion of the member 12 as shown in dotted lines in Fig. 1. The baffle member 18 extends completely across the inside of the pot 10, directly in front of the opening of the member 12 and a slight distance forward of the same.

The numeral 19 designates a horizontal row of passageways in the baffle member 18 and in close proximity to the lid 11. The forward end of the pot 10 is rounded outwardly as shown in Fig. 1 and extends from its upper marginal edge downwardly and rearwardly, the purpose of which will hereinafter be appreciated. The numeral 20 designates a notch or cut-away portion in the top marginal edge of the front wall of the pot 10. This cut-away portion extends approximately completely across the width of the forward wall of pot. It will here be noted that the thickness of the forward wall of the pot at this cut-away portion is relatively great, thereby making the same more durable and less possibility of the same melting or burning down when the retort is in use. Also it should be noted that the inner corner of the forward wall of the pot is rounded in order that there will be less resistance to the air, fuel and flame passing out of the retort between the marginal edge of the cut-away portion and the forward end of the lid 11. The numeral 21 designates an inlet port in the rear wall of the pot 10 and in close proximity to the bottom of the pot 10. It is through this port 21 that the liquid fuel is designed to be rejected.

As is well known the fuel oil entering the pot 10 through the port 21 gasifies and the air being forced into and through the pipe 12, carries with it this gas and the same is projected out of the forward end of the retort in an ignited condition. The baffle member 18 directs the air entering the retort downwardly where it picks up the fuel gas in the retort as before stated. The reason for the row of passageways 19 in the baffle member 18 is to permit a certain amount of cool air from the member 12 to pass in a straight line from the retort.

This relatively cool air passing through the passageways 19 will follow the outline of the inner surface of the lid 11, thereby keeping the same below a critical melting temperature. This air also forms what we might term a sheet that prevents to a certain extent the hot air, gases and flame from contacting with the lid and its bill portion 15. The passageways 19, by the air passing there through also prevent carbon or soot from forming on the lid 11 or forward of the baffle member 18. By the forward end wall of the pot extending downwardly and to the rear, the lower forward end of the pot 10 will be in the rear of the main body of the frame extending from the retort, thereby keeping the same from a critical melting or dangerous temperature.

The cut-away portion 20 in the forward end wall of the pot provides a relatively large space between the same and the lid 11 for the escaping gas and flame from the retort thereby permitting the retort to function in a relatively cool condition.

The numeral 22 designates a small opening in the top of the lid 11. This opening may be used to insert a lit match or like to ignite the gas in the retort when it is desired to generate and use the same. This opening should be closed by the small inclosing blade 23 secured to the top of the lid 11 after the gas or fuel in the retort has been ignited.

From the foregoing it will readily be appreciated that I have provided an oil burner retort that will become of such temperature as to successfully gasify, liquid fuel placed therein but will not reach such a high temperature as to cause it to melt down or crack or otherwise become inoperative.

Some changes may be made in the construction and arrangement of my improved oil burner retort without departing from the real spirit and purpose of my invention, and it is my intention to cover by my claims any modified forms of structure or use of mechanical equivalents which may be reasonably included within their scope.

I claim:

1. In an oil burner retort of the "in the door" type, comprising a pot portion having side, front and back walls and having its forward wall curved outwardly and slanted forwardly and upwardly from its base, a portion of the upper marginal edge of said forward wall being cut away to provide an opening, said opening extending approximately the entire width of said forward wall to allow flame to be projected laterally as well as forwardly of the pot, a rounded thickened marginal edge formed on said forward wall forming the base portion of said opening, an oil inlet in the back wall of said pot and adjacent the bottom thereof, an air inlet in said back wall and adjacent the top thereof, an inverted disk-like detachable lid covering the entire top portion of said pot and having a portion extending forwardly a substantial distance beyond the forward wall of said pot, said forwardly extending portion being downwardly curved to throw the flame in a downward direction, and means for attaching the lid to the pot.

2. In an oil burner retort of the "in the door" type, a pot portion having a bottom; side, front and back walls, said back wall being provided with air and fuel inlets adjacent the upper and lower portions respectively; said forward wall being slanted forwardly and upwardly from its base and curved outwardly and a portion of the upper marginal edge of said forward wall being cut away to provide an opening, said opening having its marginal edge portion rounded,

said forward wall being substantially thicker than said other walls; said side walls being provided along their upper edges with lug-receiving recesses; a lid for the pot, said lid being provided with lugs for insertion in said lug-receiving recesses of the side walls of said pot, said lid having a portion extending forwardly of the forward wall of said pot and providing a space between said lid and said opening in said forward wall, said forwardly extending portion being downwardly curved at its forward end to throw the flame in a downward direction.

3. In an oil burner retort of the "in the door" type, comprising a pot portion having front, back and side walls and having its forward wall curved outwardly and slanted forwardly and upwardly from its base, a portion of the upper marginal edge of said forward wall being cut away to provide an opening approximately the width of the pot, a thickened marginal edge formed on the said forward wall, an air inlet passage-way in the rear wall of said pot and near the top thereof, an oil inlet passage-way in the rear wall of said pot and near the bottom thereof, and a detachable lid completely covering the top of said pot and extending in a downwardly curved plane a substantial distance beyond the forward wall of said pot.

EVERETT E. DEHART.
